UNITED STATES PATENT OFFICE

JOSEPHINE TIDWELL, OF ANSON, TEXAS

DESIGN FOR A LAVATORY

Application filed January 13, 1933. Serial No. 46,819. Term of patent 7 years.

To all whom it may concern:

Be it known that I, JOSEPHINE TIDWELL, a citizen of the United States, residing at Anson, in the county of Jones and State of Texas, have invented a new, original, and ornamental Design for a Lavatory, of which the following is a specification, reference being had to the accompanying drawing, forming part thereof.

Figure 1 is a view in front elevation of a lavatory, showing my new design.

Figure 2 is a view in side elevation thereof.

Figure 3 is a top plan view.

Figure 4 is a bottom plan view.

Figure 5 is a perspective view thereof.

I claim:—

The ornamental design for a lavatory as shown.

JOSEPHINE TIDWELL.
